1 Claim. (Cl. 80—14)

This invention relates to tube reducing machines in which tubing is rolled on a mandrel by grooved die rollers in order to elongate the tubing and to reduce its wall thickness and diameter.

Machines of this general type are well known and comprise a drive mechanism by means of which a roll supporting saddle is reciprocated on a horizontal frame. The saddle carries a pair of die rolls having opposed grooves adapted to do work on a tube interposed between the rolls. As the saddle reciprocates the rolls are rotated by engagement between gears or the like mounted on the rolls and racks or the like mounted on the frame on which the saddle reciprocates. A mandrel is provided which extends into the space within the grooves of the rolls and which functions to support the tube during the rolling operation. Means are provided to advance and retract the mandrel so that tubes can be placed on the mandrel. In operation, the tube being operated upon by the rolls is intermittently advanced through the rolls by means of a carriage which pushes the tube through the rolls and the tube is grasped by chucks, clamps or the like to rotate it intermittently. The dies are arranged so that they are disengaged from the tube at each end of the stroke of the saddle. During the time of disengagement of the dies when the saddle is near the inlet end of the machine, the tube being worked upon is advanced a slight distance and during the time that the tube is disengaged by the dies when the saddle is toward the discharge end of the machine, the tube is rotated through a fraction of a turn, for example, sixty degrees.

The general objects of the present invention are to provide an improved tube reducing machine, to provide a more reliable and more accurate tube reducing machine, to provide a tube reducing machine which will have increased production as compared to existing machines and to provide a tube reducing machine which will occupy a substantially smaller amount of floor space than existing machines having the capacity to handle tubing of the same size.

More specific objects include the provision of an improved saddle construction in which the die supporting rolls are readily removable; the provision of a saddle that is accurately and smoothly guided in its reciprocating movement; the provision of a saddle embodying a hydraulic pressure relief mechanism to prevent damage to the dies and the mechanism in the event of overloads; the provision of a simple and efficient drive mechanism for reciprocating the saddle in which the saddle is reciprocated by connecting rods that are maintained in tension during the working stroke of the saddle, and in which the angularity of the rods is kept at a minimum; the provision of an improved mandrel advancing and retracting mechanism whereby the mandrel may be rapidly retracted from working position to loading position and rapidly advanced to working position and in which the mandrel is accurately located with respect to the dies in the working position; the provision of improved sup-

2

ports to prevent the mandrel from buckling under the forces exerted upon it by the rolling operation and the provision of a simple yet rigid and accurate frame structure whereby the proper positioning of the mandrel is assured.

Other objects include the provision of improved carriage means for advancing the tube into the dies, the provision of improved means for holding and rotating the tube as it is being worked on by the dies; the provision of improved hydraulic mechanisms for driving the tube advancing carriage and for clamping and rotating the tubes.

Additional objects include the provision of improved means for rapidly loading a tube to be fed to the machine onto the mandrel; the provision of a loading rack for the storage of tubes disposed above the saddle and die mechanism of the machine so that it requires no additional floor space; the provision of a loading rack that can be moved out of the way rapidly and easily to give access to the saddle; the provision of means for rapidly and easily transferring a tube from the loading rack and pushing it onto the mandrel, and the provision of means whereby the mandrel in position to be loaded is disposed substantially in alignment with the pusher employed to push the tubes onto the mandrel.

Further objects and advantages of the invention will become apparent from the following description of a preferred form thereof, reference being made to the accompanying drawings. The essential characteristics of the invention are summarized in the claim.

Referring now to the drawings,

Figures 1 and 1a together constitute a side elevation of the complete machine.

Figure 2 is a side elevation of the saddle mechanism on an enlarged scale as compared to Figure 1.

Figure 3 is a vertical section on an enlarged scale through the saddle and its support taken as indicated on the line 3—3 of Figure 2.

Figure 4 is a central, longitudinal vertical section through approximately the same portion of the apparatus as shown in Figure 2 and on the same scale as Figure 2 and illustrating the arrangement of the die rolls, mandrel and chucks with respect to the work, the section being taken as indicated by line 4—4 of Figure 3.

Figure 5 is a plan view on an enlarged scale of the drive mechanism with the upper half of the housing removed, the view being taken as indicated by the line 5—5 of Figure 1a.

Figure 6 is a longitudinal sectional view on an enlarged scale of one of the tube grasping and rotating chucks, the section being taken as indicated on the line 6—6 of Figure 4.

Figure 7 is a transverse section as indicated by line 7—7 of Figure 6.

Figure 8 is a plan view on an enlarged scale of a portion of the entry end of the apparatus remote from the working rolls, the view being taken as indicated by line 8—8 of Figure 1.

Figure 9 is a plan view on the same scale as Figure 8 of an intermediate portion of the entry end of the apparatus, the view being taken as indicated by the line 9—9 of Figures 1 and 1a.

Figure 10 is a horizontal section view showing the drive mechanism for the tube advancing carriage, the support for the mandrel, and the carriage, the figure being taken as indicated by the line 10—10 of Figure 1 but on an enlarged scale.

Figure 11 is a vertical section taken as indicated by the line 11—11 of Figure 10.

Figure 12 is a transverse vertical section taken as indicated by the line 12—12 of Figure 11.

Figure 13 is a transverse vertical section taken as indicated by the line 13—13 of Figure 11.

Figure 14 is a horizontal sectional detail showing the supports for the carriage advancing screws adjacent the saddle mechanism, the section being taken along the line 14—14 of Figure 2.

Figure 15 is an enlarged vertical transverse sectional view taken on the line 15—15 of Figure 2.

Figure 16 is a vertical longitudinal section taken as indicated by the line 16—16 of Figure 15.

Figure 17 is a diagrammatic illustration of the screw and mandrel support blocks showing the sequence of movements of the carriage and the mechanism by which it spaces the support blocks.

Figure 18 is a side elevation of the mandrel loading mechanism.

Figure 19 is an end view of the mechanism of Figure 18, on an enlarged scale, the view being taken as indicated on line 19—19 of Figure 18.

Figure 20 is a transverse section through the loading rack showing the hydraulic and chain mechanism for raising and lowering parts of the rack, the section being taken on line 20—20 of Figure 18.

Figure 21 is a plan view of the loading rack taken as indicated by line 21—21 of Figure 18.

Figure 22 is a transverse section taken as indicated by line 22—22 of Figure 21.

Figure 23 is a section through the main gear taken as indicated by line 3—23 of Figure 1a.

Figure 24 is a fragmentary section through one of the carriage supporting slides, taken as indicated by line 24—24 of Figure 2.

Figure 25 is a diagram of the hydraulic system for advancing the carriage and the tube; and

Figure 26 is a diagram of the hydraulic system for rotating the tube.

General arrangement.—The general arrangement of the entire apparatus is illustrated in Figures 1 and 1a and in the enlarged views constituting Figures 2, 3 and 4. As there shown, the rolls 10 and 11 which are provided with die recesses for working on a tube T are supported in or by a saddle 12 which reciprocates on tracks 14 carried by the supporting frame structure 15. The frame structure 15 is provided with fixed racks 16. Roll 11 has gears 17 that engage the racks and the two rolls are geared together as described below so that when the saddle is reciprocated the rolls are rotated first in one direction and then in the other. The saddle is reciprocated on its tracks by means of the main drive mechanism indicated in general at 20 and disposed at the exit or discharge end of the apparatus. The main drive mechanism includes cranks 21 (see Figure 5); connecting rods 22 connect the cranks to the saddle 12. The crank shaft is rotated in the direction of the arrow in Figure 1a ordinarily at a speed of about 60 revolutions per minute, although this may be varied throughout a considerable range. The tube T is fed in from the left in the arrangement shown in the drawings and is discharged to the right so that the working stroke of the dies contained in rolls 10 and 11 takes place as the saddle moves from left to right, hence the connecting rods are in tension during each working stroke.

The tube T is supported in proper position with respect to the die rolls by a mandrel M, the tapered point P of which (see Figure 4) is disposed between the rolls when the machine is operating. The mandrel can be withdrawn so that another tube can be loaded thereon; the subframe member 25 supports the mandrel and its advancing and retracting mechanism and also supports the tube advancing means. Member 25 preferably comprises an H-beam and is secured at one end to the main frame 15 while its other end is supported on a foundation plate 26. The actual support for the mandrel and tube advancing mechanisms is provided by the tiltable frame member 27 which is also an H-beam and which is pivotally con-

nected to the subframe 25 as at 28. The tiltable frame member 27 carries the rear support 30 for the mandrel, the cylinder 31 which advances and retracts the mandrel, the mandrel locking mechanism 32 which accurately locks and retains the mandrel in its advanced positions, the tube advancing carriage 33, the tube advancing screws 34 and associated mechanisms, all of which are described in detail below.

In order to provide for convenient loading of tubes on the mandrel when it is in retracted position, a hydraulic cylinder and piston mechanism 37 is mounted on trunnions 38 carried by the subframe member 25; the mechanism embodies a piston rod which is pivotally connected as at 39 to the tiltable frame 27. Operation of the cylinder functions to raise the tiltable frame to the position shown in broken lines in Figure 1 wherein it is in alignment with a pusher mechanism indicated in general at 40 in Figure 18; the pusher is associated with a loading rack indicated in general at 41 in Figures 1a and 18. The loading rack is disposed above the saddle and main drive mechanism and is adapted to carry a supply of tubes to be operated upon by the machine. The pusher mechanism 40 is tiltable from a horizontal position to a position in alignment with the raised position of the tiltable frame 27.

The tubes are intermittently advanced through the machine by the carriage 33 and are guided and held in proper position with respect to the dies by a chuck 45 disposed adjacent to entry end of the rolls 10 and 11 and a substantially identical chuck 46 disposed beyond the delivery or exit end of the rolls 10 and 11. These chucks grip the tube and also function to rotate the tube through about 60° when the dies have completed their working stroke and are disengaged from the tube preparatory to beginning the return stroke of the saddle. Carriage 33 is operated to advance the tube step by step at the time that the saddle has completed its return stroke and is disposed at its extreme position near the entry end of the apparatus. The step-by-step operation of the carriage and the step-by-step rotation of the chucks 45 and 46 are preferably obtained by hydraulic mechanisms, the hydraulic pressure being supplied by a hydraulic system controlled in synchronism with the movement of the saddle, the parts being driven by appropriate hydraulic motors. The hydraulic circuits are described in detail below and are illustrated in Figures 25 and 26 of the drawings.

Saddle and associated mechanisms.—The actual work of reducing tubes fed into the machine is done by the die rolls 10 and 11 carried by the saddle 12. These parts and their associated mechanism are shown particularly in Figures 2, 3 and 4. As indicated in Figures 2 and 3, the saddle 12 consists of two heavy U-shaped side members 50 and 51 connected at the bottom by a connecting bar 52, the recesses in the U-shaped side members providing supports for the bearings for the necks of rolls 10 and 11 and the rolls themselves being disposed between the two side members as shown particularly in Figure 3. The bearing blocks 53 and 54 for the lower roll 11 simply rest on the bottoms of the inner surfaces of the U's and are guided by the inner vertical surfaces of the legs of the U's while the bearing blocks 55 and 56 for the upper roll 10 are guided by the inner surfaces of the vertical legs of the U's and rest on the upper surfaces of the bearing blocks 53 and 54. When the bearing blocks are so positioned, the rolls 10 and 11 are directly in engagement with each other as illustrated. The bearing blocks carry appropriate anti-friction bearings, as shown.

In order to hold the bearing blocks 55 and 56 and the roll 10 down against the forces exerted in the operation of the machine, the open ends of the U's are closed by caps 57 and 58 which are secured to the U-shaped portions 50 and 51 by pins 59 as shown. In order to retain the rolls in proper position under the large forces that are developed in operation, and at the same time to per-

mit the rolls to separate if the forces become excessive and thereby to prevent breakage of the machine, hydraulic cylinders 60 and 61 are formed in the caps 57 and 58 respectively. Pistons 62 and 63 are disposed within these cylinders and integrally formed piston rods 64 and 65 bear downwardly upon the bearing blocks 55 and 56 to maintain the desired pressure on the rolls. The pressure is maintained by check valves 66 and relief valves 67 shown diagrammatically in Figure 3 which are arranged to maintain a suitable pressure in the cylinders 60 and 61, for example, pressures of the order of 5,000 pounds per square inch are contemplated and pressure relief valves 67 are arranged to open when the pressure substantially exceeds the desired pressure. Thus, for example, if the pressure should reach 5,500 pounds per square inch, upon opening of the pressure relief valves, the pistons 62 and 63 can move upwardly within the cylinders 60 and 61, the roll 10 can lift away from the roll 11 and the possibility of developing destructive forces in the apparatus due to improper functioning of the rolling mechanism or the improper design of dies or the like is eliminated.

The saddle is supported for reciprocating movement by cross-bars 70 and 71 at the entry and exit ends, respectively, of the saddle, see Figures 2, 3, 4 and 24; these bars rest on pads or bearing surfaces 72 and 73 which, in turn, are carried by tracks 14. Sideways movement of the saddle is prevented by downwardly extending flanges 74 and 75 on the pads 72 and 73. The tracks 14 are supported by the top edges of the vertical side panels 81 of the frame 15; these panels being cut out as shown at 82 in Figures 1a and 2 to accommodate the movement of the saddle and to permit removal of the rolls.

The cross-bars are welded to wings 91 and 92 extending longitudinally from the saddle members 50 and 51, the positioning of the cross-bars at the extreme ends of the saddle giving a long base for support of the saddle and thus assuring smooth motion and accurate guiding of the saddle.

In order to rotate the rolls as the saddle reciprocates, racks 16 are mounted in the side pieces 81 at a level beneath the tracks 76 and 77, the shaft of roll 11 is extended from both sides of the machine as shown and gears 17 are keyed to the roll shaft and engage the racks; thus, as the saddle reciprocates the roll 11 is constrained to rotate and the rotation of roll 11 is transmitted to roll 10 through gears 94 on the shaft of roll 11 which engages gears 95 on the shaft of roll 10. See Figures 1a, 2 and 3.

The racks 16 are secured and vertically positioned in the frame in engagement with gears 17 by means of wedges 96 clamped between the slanting ends 97 of the racks and adjacent shoulders 98 formed by the opposed projections 99 of the side pieces 81 by means of bolts 100 which extend through the wedges into each projection. As shown in Figure 2, slanting surfaces on the wedges engage the complementary slanting surfaces 97 on the racks 16 and securely position the racks when the bolts 100 are drawn up.

By this construction, rolls 10 and 11 readily can be removed from the saddle for replacement. This is accomplished by loosening the bolts 100 and wedges 96 and removing the racks transversely from the frame. Then, with the saddle 12 positioned so that the axes of the rolls are approximately at the center of the opening 82 in the side panels 81, the caps 57 and 58 are removed and the rolls 10 and 11 lifted vertically out of the saddle.

The construction of the rolls themselves and the manner in which they operate on tubing is illustrated in Figure 4. In this figure the full line position of the saddle and rolls shows them approximately at their extreme position adjacent the entry end of the apparatus, while the broken line indicates the position the saddle takes adjacent the exit end of the apparatus. The tube T ex-

tends within the die groove of the rolls and the tapered point P of the mandrel M supports the tube against the action of the rolls. In the extreme position shown the grooves of the rolls are sufficiently large so that the rolls do not engage the tubing with any substantial pressure. When the saddle and rolls are adjacent the entry end of the apparatus, the tubing is advanced a fraction of an inch. Then as the rolls roll on the tubing toward the exit end of the machine, the grooves 101 and 102, which are progressively reduced in cross-sectional area, act on the tube to elongate it and reduce its diameter and wall thickness. When the saddle reaches the broken line position the relieved portions 103 and 104 of the grooves are adjacent the tube, and the rolls are substantially disengaged from the tube. The tube is then rotated approximately 60° so that as the rolls roll back on the previously reduced section of the tube, they round it more accurately and eliminate the formation of any fins between the dies. As the rolls approach the extreme position at the entry end of the apparatus, the rolls disengage the tube, the tube is again advanced and the operation repeated. This is carried on at a relatively high rate of speed, depending on the size of the tube, about 60 complete reciprocations per minute being customary and as much as 120 strokes being possible on small tubes.

It will be noted that the actual working portions 105 and 106 of the rolls are formed separately, these portions being held in place by studs 107 and 108 and accurately located by interfitting tongues and grooves 109, 110, 111 and 112, as shown in Figure 3. The separate formation of the die portions of the rolls provides for economy in the manufacture of dies to produce tubing of various sizes and in the replacement of worn dies.

Main drive.—The main drive for the saddle is illustrated in Figures 1a, 5 and 23. As noted above, the saddle 12 is reciprocated by connecting rods 22 which are pivotally connected to the saddle as at 113. It will be noted that the pivots 113 are disposed substantially in the plane of the center line or pass line of the rolls 10 and 11. This alignment of the pivots and the pass line minimizes the vertical components of the forces applied to the saddle.

The cranks 21 to which the connecting rods 22 are secured are driven by the main drive motor (not shown) through the reduction gearing constituting the main drive mechanism 20, which is illustrated with the top half of the housing removed in Figure 5. The drive preferably is through a flexible coupling or clutch 114, one element of which is connected to the main drive motor and the other element of which is connected to the input shaft 115. Clutch 114 preferably is a coupling of the "Airflex" type in which the friction elements are held together by pneumatic pressure and which is arranged to slip under predetermined over loads such as, for example, fifty percent (50%), thus protecting the motor and the equipment in case of jamming of the apparatus.

From shaft 115, the drive is through pinion 116, gear 117, countershaft 118, pinion 119 and gear 120 to crank-shaft 121. Cranks 21 are mounted on the ends of shaft 121 and the rotation is preferably in the direction shown by the arrow in Figure 1a so that the angularity of the connecting rod with respect to the path of movement of the saddle is kept at a minimum during the working stroke of the saddle.

It will be noted that the center lines of the shafts 115, 118 and 121 are disposed slightly below the pass line of the rolls 10 and 11 and that the gears and pinions 116, 117, 119 and 120 are disposed on either side of the pass line of the roll as shown particularly in Figure 19. This arrangement makes it possible to provide the upper half 122 of the housing 20 with a guide tube 123 through which the completed tubes can pass as they leave the machine.

Tube holding and rotating chucks.—The chucks 45

and 46 disposed at the entry and delivery ends of the apparatus, respectively, see Figures 1a and 2, function to hold the tubes as they are being operated on by the die rolls 10 and 11 and to rotate the tubes at the end of the working stroke of the dies. The chucks are arranged to assist in holding the tubes against the thrust exerted upon them during the working and return strokes of the dies, yet to permit the tubes to be advanced through the chucks. The chucks also grip the tube with sufficient firmness so that when the chucks are rotated the tubes are also rotated. Preferably the chucks are disposed close to the die rolls, chuck 45 being supported by the transverse vertical member 125 of the main supporting frame 15 while the chuck 46 is supported by the transverse vertical member 126 of the frame 15. The chucks are preferably of identical construction and accordingly only chuck 45 will be described in detail herein.

As shown particularly in Figures 6 and 7, chuck 45 comprises a housing or body 127 having a radially extending flange 128 that is bolted to the transverse frame member 125. A cylindrical portion 129 of the housing projects through the cross-member, the cross-member being recessed to receive the cylindrical portion so that the chuck can be removed and replaced simply by sliding it longitudinally out of the hole in member 125. 20 25

Cylindrical portion 129 has an internal cylindrical surface within which is disposed a hollow tubular clamping piston 130, piston 130 being provided with piston rings 131 and having sleeve portions 132 and 133 that extend through packing members 134 and 135. Ports 136 and 137 are provided in the wall of cylindrical portion 129, the arrangement being such that when fluid under pressure is admitted through appropriate fluid connections to port 136, piston 132 is moved to the right in the embodiment shown in the drawing and when fluid under pressure is admitted through port 137, piston 132 is moved to the left.

In order to provide means for clamping a tube within the chuck, a camming sleeve 138 is supported within piston 132 by means of roller thrust bearings 139. The sleeve is thus mounted for rotation with respect to the piston but is constrained by the bearing to move longitudinally with the piston. The forward, or right, end of the sleeve is enlarged as at 140 and carries a camming ring 141. Ring 141 is adapted to engage the outer camming surfaces 142 of the resilient gripping fingers 143 of the collet or gripping member 144. The fingers are provided with separately formed gripping pads 145 which engage the exterior of the tube T. Collet 144 is mounted on the end of a rotatable collet-supporting sleeve 146 which is supported for rotation within the chuck body and held against longitudinal movement by roller thrust bearings 147.

It will be seen that with this arrangement, when fluid under pressure is admitted through port 136 and clamping piston 130 urged toward the exit end of the apparatus or to the right as shown in the drawing, then the camming sleeve 138 is likewise carried to the right. Collet 144, however, is held against longitudinal movement by sleeve 146 and thrust bearings 147. The resultant relative longitudinal movement between the collet and the camming ring 141 causes the ring to urge the resilient gripping fingers 143 inwardly causing the pads 145 to grip the tube. The gripping pressure can be controlled by varying the fluid pressure admitted through the port 136, and the collet can be released by releasing fluid through port 136 and supplying fluid under pressure through port 137. It will be noted that forces exerted by frictional engagement of the tube with the collet tend to reduce the clamping forces exerted on the tube as it moves in the advancing direction (to the right in the drawing) while forces exerted by the tube in the opposite direction tend to increase the clamping pressure.

In order to rotate a tube gripped by the collet 144, the camming sleeve 138, collet 144 and supporting sleeve

146 are arranged to be rotated as a unit with respect to the body 127. Rotation is accomplished by a worm wheel 143 which is keyed to sleeve 146; the worm wheel is rotated by worm 149 which is supported by appropriate bearings 151 and 152 in an enlarged portion 153 of the housing 127. The worm in turn is driven through a suitable coupling 154 by a hydraulic motor 155 (see Figure 2). Motor 155 is of the positive displacement type, suitable hydraulic motors being manufactured by the Vickers Manufacturing Company of Detroit, Michigan, so that for a given volume of fluid passing through the motor, the motor makes a given number of revolutions. Thus by supplying the same quantities of liquid to the motor 155 of chuck 45 and the motor 156 of chuck 46, they can be caused to rotate each of the chucks or gripping jaws through the same number of degrees. The hydraulic circuits whereby the motors for the chucks 45 and 46 are rotated through the desired number of revolutions in proper time relationship with the movements of the saddle are described below. When the sleeve 146 and collet 144 are rotated, the sleeve 138 also rotates because of the frictional engagement between the clamping ring 141 and the outer camming surfaces 142 of the fingers 143 of the collet.

25 *Tube feeding carriage and associated mechanism.*—Tubes mounted on the mandrel M are pushed forward in a step-by-step motion through the die rolls and chucks by the tube feeding carriage 33 which travels along the tiltable frame member 27 from its rearmost position
30 shown in Figure 1 to a position adjacent the saddle mechanism and main frame 15. As shown in Figures 8, 10, 11 and 13, the carriage 33 comprises a block 160 extending transversely of the frame member 27 and having a central recess 161 provided with a shoulder 162 acting as a stop abutting the rear end of the tube T, the recess 161 continuing in reduced diameter toward the rear of the machine from shoulder 162 to provide a passageway for the mandrel M. During normal operation, the tube T is held within opening 161 of the carriage 40 and against shoulder 162 by the compressive forces resulting from the forming rolls acting on the tube and hence no other locking means is necessary to secure the tube to the carriage. However, in the event it should become necessary to withdraw a partially reduced tube 45 from the machine as, for example, when the tube is faulty, the tube must be clamped to the carriage as the latter is withdrawn. For this purpose, a set screw 163 is threaded into the block 160 and is adapted to clamp the end of the tube T to hold it in the recess 161 when
50 the carriage 33 is moved away from the rolls.

On either side of the recess 161, the block 160 is provided with generally rectangular recesses which receive nuts 164 (see Figure 10) that are threaded on the longitudinally extending carriage drive screws 34. Nuts 164 are retained in position within the block by flanges 165 and 166 on the front and rear sides of the carriage, respectively.

In order to support the carriage in its travel along the frame member 27, a plate 167, see Figure 13, is welded 60 to the horizontal web 168 of the frame member 27, the plate 167 extending substantially throughout the length of travel of the carriage. Slides 169 preferably composed of brass or a similar metal are suitably secured to the upper surface of the plate 167; the lower surfaces of 65 the nuts 164 slide along and are supported by the upper surfaces of the slides.

With this arrangement, rotation of the screws 34 in one direction causes the carriage to advance toward the saddle mechanism 12 while rotation of the screws in the opposite direction causes the carriage to retract. In order to support the screws 34 for rotation, the forward ends of the screws adjacent the saddle 12 are mounted in thrust bearings 171, see Figure 14, which are mounted in blocks 172 secured to the end plate 173 of the tiltable

frame 27. The rear ends of the screws 34 are supported by ball bearings 174, which are mounted in the housing 175 at the rear end of the frame member 27, see Figures 8 and 10. It will be noted that the screws 34 have unthreaded shank portions 176 extending from the rear-most position of the carriage 33 to the bearings 174 and that these unthreaded shanks are enclosed in sleeves 177. As will appear more fully below, these sleeves act as slides for the support of the rear mandrel support 30.

In order to provide for rotation of the screws 34, each screw has mounted on it a gear 180 (see Figure 10); the gears 180 mesh with a centrally disposed pinion 181 mounted on a stub shaft 182 carried by suitable bearings in the housing 175. Shaft 182 is driven through a suitable coupling 183 (see Figure 11) by a hydraulic motor 184. Motor 184, like motors 155 and 156, is of the positive displacement type so that the number of revolutions of the motor can be accurately controlled by regulating the volume of liquid supplied to it. The hydraulic circuits whereby the motor 184 is operated in proper time relationship with the motion of the saddle to advance the carriage and hence the tubes with an intermittent or step-by-step motion are described in detail below. For the present, it will be sufficient to say that the motor is arranged to rotate the screws 34 sufficiently to advance the carriage 33 a short distance, for example, about $\frac{1}{4}$ of an inch, each time the saddle reaches the end of its return stroke and as it begins its working stroke toward the delivery end of the machine. The motor is also arranged so that it can be operated continuously at comparatively high speed to retract the carriage from the saddle in order to provide for loading another tube on the mandrel and to advance the carriage to the desired position after the tube has been loaded.

The rolling forces react through the tube to the carriage and similar reactions occur in the mandrel. Inasmuch as the screws and mandrel may be many feet long, it is desirable to provide supports for these members intermediate their ends in order to prevent the members from sagging of their own weight and to prevent them from buckling because of compressive forces applied to them. To this end, supporting blocks 190, 191, 192 and 193 (see Figures 1, 8, 9 and 11) are associated with the carriage 33. These blocks slidably engage the screws 34 and the mandrel M; blocks 190 and 191 are arranged to be dropped off at spaced intervals as the carriage advances toward the saddle and picked up again on the return trip of the carriage while blocks 192 and 193 are arranged to be picked up as the carriage advances toward the saddle and dropped off at spaced intervals in the locations shown in Figures 1 and 9 when the carriage is retracted. The blocks are of substantially identical construction and extend transversely of the frame member 27. They are built in halves (see Figure 11), the lower half of each block being indicated at 194 and the upper half at 195. The parting line of the halves of the blocks coincides substantially with the horizontal plane of the center lines of the screws 34 and the mandrel M, the halves 194 and 195 being provided with complementary semi-cylindrical recesses which provide openings 196 (see Figure 10) for the screws 34 and an opening 197 for the mandrel M. The two halves of the blocks are secured together by bolts or screws 198. The openings 196 are preferably lined with bearing sleeves 199 which engage the threads of the screws 34 while the openings 197 simply slidably receive the mandrel M.

In order to carry the blocks to their desired stations along the frame member 27, the carriage is provided with two rearwardly extending latches 201 (see Figure 10) and two forwardly extending latches 202. Latches 201 and 202 are pivotally mounted on the carriage 33 by means of the screws 203; lugs 204 (see Figure 13) project from the body of the carriage to prevent the latches from dropping below substantially horizontal position. The ends of the latches are provided with ver-

tical shoulders 205 and 206, respectively (see Figure 17) and inner camming surfaces 207 and 208 and outer camming surfaces 209 and 210 on the latches 201 and 202, respectively. Dogs 211 and 212, see Figure 9, which are arranged to actuate the latches as the carriage travels along the frame 27, are disposed on the frame adjacent the points where it is desired to locate the supporting blocks as the carriage moves back and forth.

The operation of the latches is illustrated somewhat diagrammatically in Figure 17 of the drawing in which successive positions of the carriage and blocks as the carriage travels from its rear position as shown in Figure 1 toward the saddle are illustrated at A, B, C and D.

At A in Figure 17 the carriage is starting out from its rearmost position. Latches 201 are in engagement with pins 213 which project from block 190, the shoulders 205 of the latches engaging the pins. Latches 202 are supported by lugs 204 in a substantially horizontal position and blocks 192 and 193 (not shown in diagram A) are disposed adjacent dogs 211 and 212 as shown in Figure 1. Intermittent rotation of the screws 34 by the motor 184 advances the carriage 33 step by step and the parts remain in the relationship shown in diagram A with the blocks 190 and 191 travelling along with the carriage until the latches 202 approach the block 192 adjacent the dogs 211. At this point, the outer camming surfaces 210 of the latches 202 engage the pins of block 192 and the latches are lifted upwardly over the pin so that the forward motion of the carriage continues without displacing block 192 until the forward face of the carriage 33 engages the rear face of block 192, after which the block is carried forward with the carriage, occupying the position shown in diagram C.

Blocks 190 and 191 are carried along with the carriage 35 until the inner camming surfaces 207 of latches 201 engage the sloping rear surface of dogs 211 as shown in diagram C. Dogs 211 lift the latches upwardly until the shoulders 205 clear the pins 213. Continued movement of the carriage then causes the pins 213 to engage the inner surfaces 207, lifting the latches to clear the pins so that the block 190 is released from the latches and, as the carriage moves on, is left in the desired position adjacent the dogs 211, as shown in diagram D.

When the block 190 has been released by the latches 45 201, the block 191 remains stationary until the pins 216 projecting therefrom engage the shoulders of the latches 211. This condition is shown in diagram D wherein block 190 has been left adjacent dogs 211 and the carriage is progressing, pushing block 192 ahead of it and pulling block 191 by means of the latches 201. The carriage progresses in this fashion until block 193 and dogs 212 are reached. Here the latches operate in the manner described above; latches 202 ride over pins 218, the carriage picks up block 193 and pushes it ahead. Then, when latches 201 reach dogs 212, the latches are lifted upwardly to release block 191, leaving it in substantially the position previously occupied by block 193.

On the return trip of the carriage, the same type of operation takes place, the carriage picking up blocks 191 and 190 and dropping off blocks 193 and 192.

With this arrangement, the unsupported spans of the screws 34 and the mandrel M can be kept to reasonable lengths and the parts can be restrained from buckling under the influence of the rolling forces, or from sagging because of their own weight. As many blocks can be utilized as required by the length of the machine. It is to be noted that the blocks 190 and 191 on the rear side of the carriage 33 are dimensioned to fit the mandrel closely while blocks 192 and 193 on the forward side 65 of the carriage are dimensioned to fit the tube surrounding the mandrel.

As will appear below, the mandrel is supported at its rear end; hence, it is subjected to buckling because of compressive forces imposed upon it. The screws 34, 70 however, have thrust bearings only at their forward ends

adjacent the frame 15 and are subjected only to forces in tension during the working stroke and advancing movement of the carriage. The screws, therefore, function to retain the blocks in proper position on the tracks 182 against lateral or vertical forces exerted by the mandrel. 5

Mandrel advancing and retracting mechanism.—In order to provide for loading additional tubes onto the mandrel, the mandrel must be supported so that it can be moved from the retracted position shown in Figures 1 and 1a to the advanced or working position in which the tapered end of the mandrel is disposed between the die rolls as shown in Figure 4.

The required movement of the mandrel is accomplished by mounting the rear end thereof on the mandrel support 30 (see Figures 1, 8, 11, 12 and 13). As shown particularly in Figures 11 and 12, the mandrel support 30 comprises a T-shaped body, the vertical leg 230 of the T extending through the slot 231 in the web of the frame member 27 and the horizontal portion of the T being constituted by a horizontal portion 232 formed integrally with the leg 230 and a cap portion 233 bolted thereto. Portions 232 and 233 are provided with semi-circular recesses which, when the parts are assembled, define cylindrical recesses 235 which receive the carriage advancing screws 34 and sleeves 177 which support and guide the mandrel support 30. Portions 232 and 233 also have semicylindrical recesses which define a central cylindrical recess 236 that is internally threaded to receive the externally threaded mandrel supporting sleeve 238. Sleeve 238 in turn supports thrust bearing 239 which carries the rear end 237 of mandrel M. Bearing 239 is locked against longitudinal movement with respect to sleeve 238 by engagement of the outer race thereof with shoulder 240 of the sleeve and spacer 241 which is retained in position by nut 242. The inner race of bearing 239 is secured to the end 237 of the mandrel. Between the point P and the rear end 237, the mandrel M is hollow and is provided with a threaded plug 243 that is screwed into the end 237; this makes it possible to replace mandrels without disturbing the bearing 239.

The support for the mandrel is such that by rotation of the sleeve 238, the longitudinal position of the mandrel M with respect to the rear mandrel support 30 may be adjusted readily. Sleeve 238 may be rotated by means of a spanner engaging nut 242 or by means of an appropriate wrench engaging nut 244 secured to plate 245 which is welded to the interior of the sleeve. The sleeve is locked in its desired position by the clamping mechanism indicated at 246. This adjustment of the longitudinal position of the mandrel enables the operator to locate the point P accurately with respect to the rolls 10 and 11.

In order to advance and retract the mandrel, the fluid pressure actuated cylinder 31 is preferably employed; a cylinder engages the depending leg 230 of the support 30 and is disposed beneath the web 168 of the tiltable frame member 27. As shown particularly in Figure 11, the cylinder 31 passes through a cylindrical opening in the leg 230 and is retained against longitudinal movement by snap rings 251. A piston 252 is disposed within the cylinder and is mounted upon a hollow piston rod having end portions 253 and 254 which project through cylinder heads 255 and 256, these being provided with suitable packings; the ends of the piston rods are secured to brackets 257 and 258 which are welded to the underside of the web of the frame member 27. Fluid under pressure can be admitted to either side of the piston 252 through conduits 259 and 260 and ports 261 and 262, the bore of the tubular piston rod being blocked by a plug 263 between the ports 261 and 262 and within the piston 252. Thus, when fluid under pressure is admitted through conduit 259 into cylinder 31 and fluid in the cylinder is permitted to be discharged through conduit 260, the cylinder is moved to its extreme retracted position to the left as shown in the drawings, while when the connections

are reversed, the cylinder is moved to its extreme advanced position to the right as shown in the drawings. The piston and piston rods remain stationary at all times, making it unnecessary to employ long lengths of flexible conduit to supply the interior of the cylinder with fluid.

In order to roll tubing to accurate diameters, the tapered end portion of the mandrel must be located accurately with respect to the die rolls when the mandrel is in advanced position and must be securely locked to withstand the forces imposed upon the mandrel during the rolling operation. To accomplish these results, the cap portion 233 of the mandrel support 30 is extended upwardly as shown at 265, Figures 11 and 12, and the webs of the upwardly extending portion 265 are cut away as shown at 266 to provide arcuate seating surfaces. These seating surfaces are arranged to be engaged by a semi-cylindrical locking member 32 which is supported in appropriate bearings carried by brackets 268 extending upwardly from the frame member 27 and preferably welded thereto. Locking member 32 is rotatable, by a positive displacement hydraulic motor 269, between the released position shown in Figures 1 and 11 and a locked position in which the semi-cylindrical central portion 267 thereof is turned about 180° from the position shown down into locking engagement with the arcuate surfaces 266 of the upward extensions 265 of the mandrel support 30. When this massive locking member is turned downwardly into locking engagement with the mandrel support, the mandrel support is firmly held in an accurately predetermined position. By making suitable adjustments of the mandrel supporting sleeve 238, the tapered end portion of the mandrel can be adjusted to the desired position; the locking member retains the mandrel in its desired location whenever it is in advanced or working position. When it is desired to retract the mandrel, the motor 269 is operated to rotate the locking bolt upwardly and out of engagement with the surfaces 266 whereupon the carriage 30 and mandrel may be retracted by operation of the cylinder 250. After the mandrel has been loaded, it is only necessary to operate the cylinder 250 to advance the mandrel and operate the motor 269 to rotate the locking bolt into locking position, thereby accurately locking the mandrel in working position.

Mandrel loading mechanism.—As explained briefly in the description of the general arrangement of the apparatus, after a tube is advanced through the die rolls until the rear end of the tube approaches the chuck 45, the machine is stopped, the mandrel M withdrawn to its retracted position by operation of the cylinder 250 and the tiltable frame member 27 then tilted about the axis provided by pivot 28 to place it in alignment with the pusher mechanism 40 as indicated in broken lines in Figure 18. As shown in Figure 13, the pivot 28 comprises a massive bar supported in bearings 270 carried by subframe member 25, the frame member being reinforced by brackets 271 at this point. The ends of the pivot 28 are engaged by brackets 272 which are welded to the web 168 of the tiltable frame member 27, thus providing a strong pivotal support for the member 27.

The construction of the front end of the tiltable frame member 27 and the means for aligning it with the base frame 25 and the main frame 15 are illustrated in Figures 9, 15 and 16. As shown particularly in Figure 9, the web of the tiltable frame member 27 is slotted as at 274; the apparatus is stopped for re-loading after the rear end of the tube being reduced has cleared the web 168 and is adjacent the slot 274. In retracted position, the tapered end P of the mandrel M is withdrawn slightly beyond the end of the slot 274 so that when the mandrel is withdrawn it is disengaged from the tube carried by the chuck, permitting the frame 27 and mandrel to be tilted without interfering with the tube.

In order to align the frame member 27 with the subframe 25 and main frame 15, the end plate 173 which supports blocks 172 and bearings 171 for the screws 34

is provided with a downwardly extending tongue 275, the tongue being centrally slotted as at 276 to provide a passage aligned with the slot 274 in the web 168. The ends 277 of tongue 275 are accurately machined and rest upon the upper machined face 278 of locating block 279 which is welded to the web of the subframe member 25 adjacent the end thereof that is welded to the frame member 15. The side vertical surfaces 280 of the tongue are guided by the upstanding webs of subframe 25. Thus, when the tiltable frame member 27 is in lower or operating position, its forward end is accurately located in both vertical and horizontal planes so that the axes of the mandrel and a tube on the mandrel will coincide with the center line of the chucks 45 and 46 and the pass line of the die rolls 10 and 11. As noted above, the front end of the subframe is raised and lowered by the hydraulic cylinder 37.

In order to provide a convenient means of storing a supply of tubes adjacent the machine and of loading the mandrel rapidly and efficiently, the loading rack 41 (see Figures 1a and 18) and associated pusher mechanism 40 are supported above the main frame 15 and the drive mechanism 20. This arrangement makes it possible to store the tubes in a most convenient location and at the same time requires practically no additional floor space for the loading rack and associated mechanisms. The loading rack and associated mechanism are supported, so that they can be moved away from their normal position above the working parts of the machine to give overhead access to the machine, by curved supports 282 (see Figures 18 and 19) on one side of the machine, these having horizontally extending portions 283 which are secured to straight vertical supports 284 on the other side of the machine. The curved supports 282 and the straight supports 284 are mounted on wheels 285 which run on tracks 286 disposed on either side of the apparatus and extending parallel to the longitudinal axis of the apparatus. Thus, the loading rack and associated mechanism can be pushed out of the way whenever it is desired to have access from above either to the main drive 20 or to the saddle 12 and associated mechanisms.

As shown in Figures 18, 21 and 22, the loading rack 41 comprises several longitudinally spaced transversely extending sloping support members 289 adapted to carry a number of tubes T and deliver them to the pusher mechanism indicated in general at 40. The tubes are prevented from rolling off the loading rack by a series of stops 290 (Figures 21 and 22) at the ends of supports 289 adjacent the pusher 40. In order to deliver the tubes singly to the pusher a plurality of arms 291 are mounted upon a rock shaft 292 extending longitudinally beneath the loading rack, the arms projecting upwardly through slots 293 in the loading rack (Figure 22). The rock shaft is operated by hydraulic cylinder 294 through crank arm 295. When the arms 291 are in their lowermost position as shown in full lines in Figure 22, one of the tubes T will rest against the stops 290, the other tubes T lying, for example, as shown in the drawing. When the cylinder is operated to raise the arms upwardly to the position shown in broken lines, the ends 296 of the arms lift the last tube to a level above the stops 290 as indicated in dot-dash lines; the tube then rolls downwardly along the sloping upper surface of the ends 296 and the correspondingly sloped surface of the stops 290 onto the channel-section track 297 of the pusher mechanism. The next tube then rests against the surfaces 298 of the arms until the arms are withdrawn by operating the cylinder 294 in the reverse direction, whereupon the tubes roll down against the stops 290 in position for a subsequent operation of the arms 291.

The pusher mechanism comprises the track 297 which is mounted upon a box section member 299 that is pivotally supported by pivot 300 (see Figures 1a and 18) at the delivery end of the machine and by a yoke 301 secured to a chain 302 which passes over sprockets 303

and is connected at its other end to the piston rod 304a of the hydraulic piston and cylinder mechanism 304 mounted on the upright 284 nearest the entry end of the machine (Figures 18, 20 and 22). Box section member 299 has within it a channel 305 which supports the lower reach of pusher chain 306, the upper reach being supported by channel 297. The upper reach of chain 306 carries a pusher head 308 that is adapted to engage the end of a tube and push it onto the mandrel. The chain is guided at the entry end of the machine by sprocket 309 and at the delivery end of the machine passes over idler sprocket 310 and driving sprocket 311 which is driven through gear reducer 312 by motor 314 (see Figure 19). Motor 314 is reversible and is provided with appropriate controls so that the chain can be driven in a direction to carry the pusher head 308 toward the mandrel to push a tube onto the mandrel and then reversed to carry the head 308 back toward the motor ready for another pushing operation.

It will be noted that the loading rack is longitudinally horizontal and that the box member 299 and channel 297 are also horizontal when the arms 291 are operated to deliver a tube to the track 297. In order to align the track 297 and a tube carried thereby with the mandrel M, the hydraulic piston and cylinder mechanism 304 is operated to lower the adjacent end of the box section 299 and the track 297 about the pivot 300 until the center line of a tube carried by the track is substantially in alignment with the center line of the mandrel which has been raised by upward tilting of the titlable frame member through the action of lift cylinder 37. In this position, as shown in Figure 18, it will be seen that the box section 299 extends downwardly through the slot 274 in the web 168 of frame member 27 and is provided with a rearwardly and laterally extending tongue member 315 which rests on the web of frame member 27, thus properly aligning the track 297 with the mandrel M so that the tube can be fed onto the mandrel without difficulty.

As soon as the tube is fed onto the mandrel the pusher is retracted to its position near the motor ready for another operation, the box member is raised to horizontal position in alignment with the loading rack by the operation of cylinder 304, the tiltable frame member 27 is lowered by cylinder 37 into its operating position, the mandrel is advanced to operating position and the carriage advanced to operating position, whereupon the main drive is started and the progression of the tubes through the apparatus resumed.

Hydraulic circuits.—As explained above, the tubes are advanced through the apparatus and rotated by positive displacement fluid pressure motors. By controlling the amount of fluid passing through such motors the distance the tubes are advanced and the amount of rotation of the tubes during each complete cycle of reciprocation of the carriage can be accurately determined.

Figure 25 diagrammatically illustrates the hydraulic circuits for controlling the operation of the fluid motor 184 which rotates screws 34 and thereby advances and retracts the tube advancing carriage 33. Hydraulic fluid under pressure is supplied to the motor 184 by electric motor 325 which drives a pump having a high volume section 326 and a low volume, high pressure section 327. When the tube is to be advanced intermittently through the apparatus the solenoid valve 328 is de-energized so that the discharge of the large volume section 326 of the pump is simply directed back to the sump through the pressure relief valve 329. The output of the high pressure section 327 is delivered through the check valve 330 to the accumulator 331 and to conduit 332 leading to the control valve 333. With the solenoid 334 of the pilot valve 335 energized the control valve 333 takes the position shown and the line 332 is connected to the motor 184 in such a manner as to rotate the motor in tube advancing direction.

The rotation of the motor is initiated by momentarily energizing the solenoid 336 of the pilot valve 337. When this solenoid is energized the cylinder control valve 338 takes the position shown and fluid exhausted from the motor 184 flows through the valve 333, conduit 339 and valve 338 to the metering or control cylinder 340. The flow continues until the metering cylinder reaches the end of its stroke whereupon the flow of fluid, and correspondingly the rotation of the motor 184, is stopped.

Piston 341 of metering cylinder 340 is connected by means of piston rod 342, adjustable connection 343 and piston 344 to piston 345 of metering cylinder 346, which is substantially identical with metering cylinder 340. The stroke of piston 341 moves piston 345 to the head of cylinder 346, the fluid within cylinder 346 being discharged through control valve 338, line 347 and check valve 348 to the sump. Adjustable connection 343 may be varied to change the total length of piston rods 342 and 344 and vary the stroke of pistons 341 and 345; each piston acts as a stop for the other, hence the longer the total length of the piston rods, the shorter the strokes of the pistons and vice versa. Thus, the volume of fluid displaced in each stroke of the pistons 341 and 345 and the amount of rotation of the fluid motor 184 may be accurately controlled.

The next operation of the motor 184 is obtained by energizing the solenoid 349 of pilot valve 337. This reverses the position of control valve 338 so that fluid can be discharged from the motor 184 through the valve 333, line 339 and valve 338 to cylinder 346. Piston 345 thereupon moves to the left to the end of its stroke, returning to the position shown in the drawing, motor 184 rotates the predetermined amount, piston 341 is returned to the position shown in the drawing and the fluid in cylinder 340 is discharged through the reversed connections of valve 338, line 347 and check valve 348. Thus by alternately energizing solenoids 336 and 349 the motor 184 can be caused to operate intermittently in the desired time relationship with the motion of the saddle to advance the tube through the apparatus.

In loading additional tubes into the apparatus it is necessary rapidly to advance and retract the tube advancing carriage 33. Rapid operation of the motor 184 is obtained by energizing solenoid 351 of valve 328 so as to direct the discharge of the large volume section of the pump into the system through check valve 352. The direction of rotation of the motor is determined by pilot valve 335, energization of solenoid 334 operating the control valve 333 to provide for forward rotation of the motor, and energization of the solenoid 353 operating the valve 333 to cause reverse rotation of the motor. The duration of the operation of the motor is controlled by energization of solenoid 355 which controls pilot valve 356 which in turn controls valve 357. In the position shown in the drawing valve 357 simply blocks the flow of fluid through line 358 and hence prevents discharge of fluid from the pump directly to the sump; this is the condition that obtains when solenoid 355 is not energized. When solenoid 355 is energized, however, the position of valve 357 is reversed and fluid can flow from line 358 through valve 357, line 359 and check valve 348 to the sump. The motor 184 operates continuously as long as solenoid 355 is energized; the direction of rotation of the motor is controlled by solenoids 334 and 353, and sufficient fluid can be supplied to operate the motor at high speed by energizing solenoid 351.

The hydraulic motors 155 and 156 for rotating the chucks 45 and 46 and thus rotating the tube are as shown in Figure 26, controlled by mechanisms generally similar to the controls just described for the hydraulic motor 184, in that the amount of rotation of the motors is controlled by metering cylinders which accurately control the amount of the fluid permitted to flow through the motors in any given cycle of operation.

The fluid under pressure for operating hydraulic motors 155 and 156 is supplied by an electric motor 360 driving a pump 361. The line 364 from pump 361 is connected to pressure relief valve 365 and includes a check valve 366. An accumulator 367 is charged during the periods of low volumetric demand; discharge from the accumulator augments of the pump delivery during periods of greater volumetric demand.

Beyond the accumulator, line 364 branches into lines 368 and 369 which lead to motors 155 and 156. Needle valves 370 and 371 are included in lines 368 and 369 to govern the rate of flow of fluid to the motors and hence the speed of operation of the motors.

The hydraulic fluid discharged from motor 155 flows through line 372 and control valve 373 to the metering or control cylinder 374. In the position shown in the drawing, solenoid 375 of pilot valve 376 has been momentarily energized and control valve 373 set to the position shown so that fluid discharged from the motor 155 flows through line 379 to the left-hand end of the double-acting metering cylinder 374. Control valve 373 also opens communication from the right-hand end of cylinder 374 through line 380 and check valve 381 to the sump, thus permitting the piston 381 to move to the right in the embodiment shown until it reaches the end of its stroke and thereby permitting the discharge of a measured quantity of fluid from the motor 155 and a predetermined amount of rotation of the motor.

At the same time that motor 155 is operating, solenoid 382 of pilot valve 378 has been energized, placing the control valve 383 in the position shown and permitting fluid to flow from motor 156 through line 384, valve 383 and line 385 to the left-hand end of the double-acting metering or control cylinder 386. Piston 387 in cylinder 386 moves to the right and the fluid in the right-hand end of cylinder 386 is discharged through line 388, valve 383 and check valve 389 to the sump. Thus a measured quantity of fluid is permitted to flow through motor 156 and the motor driven for a predetermined number of revolutions. Cylinders 374 and 386 are identical in size and the piston rods 390 and 391 of the pistons 374 and 387 are connected through the adjustable connection 392 so that the pistons are constrained to move together and for identical distances. The strokes of the piston can be adjusted by adjusting the connection 392 and changing the effective length of the piston rods thereby. Since the two pistons displace the same amount of fluid in each stroke, the two motors 155 and 156 are constrained to operate simultaneously for the same amount of rotation and a single adjustment controls the amount of rotation of both motors.

For the next operation, solenoids 393 and 394 are energized so that pilot valves 376 and 378 are controlled to shift the position of the control valves 373 and 383 so that fluid from line 372 is discharged through control valve 373 and line 389 into the right-hand end of cylinder 374 while fluid from the motor 156 is discharged through line 384, control valve 383 and line 388 to the right-hand end of cylinder 386. The pistons 381 and 387 then move together to the left in their respective cylinders and fluid is discharged from the cylinders to the sump through lines 379 and 385, valves 373 and 383 and check valves 381 and 389. The motors stop upon the completion of the strokes of the pistons to the left and then the apparatus is in condition for another cycle of operations by energization of solenoids 375 and 382 and movement of the pistons 381 and 387 to the right. Thus the motors can be operated periodically to rotate the tube by alternate energization of solenoids 375 and 382 and solenoids 393 and 394.

Operation of the motor 184 for advancing the tube and of motors 155 and 156 for rotating the tube is effected at the proper times in the cycle of operation of the saddle 12 by energizing the solenoids 336 and 349 for controlling the motor 184, the solenoids 375 and

393 for controlling the motor 155, and the solenoids 382 and 394 for controlling the motor 156 in timed relationship with the reciprocation of the saddle. This is accomplished by means of a rotary switch 396 which may be of any conventional construction. Switch 396, as shown in Figures 1a and 23, is mounted on the main drive housing 20. The switch is driven from the crank-shaft 121 by pinion 397 which engages gear 398 mounted on countershaft 399. Shaft 399 is provided with a sprocket 400 which drives sprocket 401 on the switch through chain 402. It will be noted that the pinion 397 is half the diameter of gear 398 and sprockets 400 and 401 are of equal diameter so that the shaft of the switch is rotated at half the speed of the crankshaft 121.

The switch shaft is provided with contactors which make momentary contact with stationary contacts carried by the housing of the switch once each revolution. Pairs of contacts are provided for control for each of the solenoids 336, 349, 375, 382, 393 and 394. In order to control the motor 184 the contacts are arranged so that upon one revolution of the crankshaft 121 the solenoid 336 is energized as the saddle approaches its extreme position toward the inlet end of the apparatus and on the succeeding revolution of the crankshaft the solenoid 349 is energized as the saddle approaches its same extreme position toward the inlet end of the apparatus. Since the shaft of switch 396 revolves at half the speed of crankshaft 121 the contacts for solenoids 336 and 349 are spaced 180° apart, thus achieving the desired alternate operation of the solenoids and intermittent operation of the motor 184 as the tube is released from the rolls 10 and 11 at the inlet position of the saddle.

The solenoids for controlling the motors 155 and 156 are momentarily energized in a similar fashion. Thus during one revolution of the crankshaft 121, when the crank takes the position that brings the saddle to its extreme position toward the discharge end of the apparatus, the switch completes circuits energizing solenoids 375 and 382 and causing motors 155 and 156 to operate. When the saddle approaches the same position on the succeeding revolution of the crankshaft, the switch completes circuits energizing solenoids 393 and 394, thus again causing the desired rotation of motors 155 and 156. As before, the contacts for solenoids 393 and 394 are 180° apart from the contacts for solenoids 375 and 382. Switches of the type described are provided with adjustments so that the instant of energization of the several solenoids can be accurately controlled.

Thus by the hydraulic circuits shown and the electrical controls therefor just described, the hydraulic motors 184 and 155 and 156 can be operated to advance the tube the desired distance during each cycle of reciprocation of the saddle and to rotate the tube through the desired number of degrees during each reciprocation of the saddle. The timing can be carried out accurately through the switch 396 and the amount of advancement and rotation can be controlled accurately by adjustment of the adjusting couplings 343 and 392.

Summary of operation.—Assuming that a supply of tubes has been deposited on the loading rack 41, the apparatus is placed in operation by operating the cylinder 294 (see Figure 22) to raise the arm 291 so that a tube rolls off the rack onto the track 297 of the pusher, suitable, centrally located push button controls preferably being provided for the various cylinders and motors incorporated in the apparatus. The pusher is then lowered to the broken line position shown in Figure 18 and the tiltable frame 27 is moved up into alignment with the pusher by means of the cylinder 37, the mandrel support 30 and mandrel M having been previously retracted to the position shown in Figures 2, 8 and 9 by means of cylinder 31. With the parts in this position the pusher motor 314 is operated to push a tube blank onto the mandrel. Depending upon the length of the tube blanks,

more than one blank may be loaded onto the mandrel by repeated operations of the pusher mechanism.

After the desired number of blanks have been loaded onto the mandrel the tiltable frame 27 is lowered to a horizontal position, the mandrel is advanced by means of cylinder 31 and locked in working position by means of the locking mechanism 32.

The rear end of the rearmost tube blank is engaged within the recess 161 in the tube advancing carriage 33 (Figures 8, 10 and 11) and the tube advancing carriage is moved forward to place the foremost tube adjacent the bight of the rolls 10 and 11 by means of the tube advancing screws which are operated at high speed by hydraulic motor 184. After the leading end of the first tube blank has been brought to position adjacent the bight of the rolls with the saddle in its extreme position toward the entry end of the machine, reciprocation of the saddle is started and the carriage then operated automatically in timed relation with the saddle by means of the hydraulic mechanism shown in Figure 25 to advance the tube through the apparatus a short distance as the saddle approaches the extreme position toward the entry end of the apparatus. As the tube is advanced the reciprocation of the saddle causes the rolls 10 and 11 to roll the tube to a smaller diameter and to elongate it, the internal diameter of the tube being governed by the tapered point P of the mandrel.

The principal work upon the tube is done as the saddle moves from its extreme position near the inlet end of the machine to its extreme position near the exit end of the machine. As the saddle approaches its extreme position near the exit end of the machine, the tube is released from the rolls by reason of the relief in the grooves of the roll and at this portion of the stroke the tube is rotated through a fraction of a revolution by rotation of the chucks 45 and 46 which are driven by hydraulic motors 155 and 156 in proper timed relationship in movement with the saddle through the hydraulic mechanism shown in Figure 26. Initially the first tube is held only by chuck 45 but as the rolling operation progresses the leading end of the tube enters and is gripped by chuck 46. The gripping pressure exerted on the tube by the chuck is controlled, by controlling the pressure of the fluid supplied to the clamping piston 130 of the chuck, to be sufficient to grip the tube firmly and rotate it positively but at the same time to permit the tube to be pushed forward through the chucks.

The operation of the rolls may be continued until the last tube blank loaded onto the mandrel reaches a point where its trailing end is approaching chuck 45 and is beyond the end of the mandrel when the mandrel is in retracted position. When the tube has been advanced to this point, the operation of the saddle is stopped, the mandrel is retracted by cylinder 31, the tube advancing carriage 33 is retracted by rapid operation of the motor 184 through the controls shown in Figure 25, the tiltable frame 27 raised to its loading position and the loading operation carried on as before, whereupon the entire cycle of operations can be repeated.

From the foregoing description of a preferred form of the invention it will be seen that the invention provides an improved tube reducing machine which is of sturdy design and construction and operates to reduce tubing in diameter accurately at an increased rate of production. The machine is arranged so that it can be operated readily by one man and, because of the ease of loading tubes onto the machine, the time taken in loading the machine is reduced as compared to prior types of machines and increased production of tubing is obtained. Because of the arrangement of the loading mechanism with the loading rack disposed above the saddle, made possible by the tiltable frame 27, the machine occupies a substantially smaller amount of floor space than required by existing machines of similar capacity. The arrangement of the drive mechanism insures

smooth and accurate movement of the saddle, the pressure relief mechanism incorporated in the saddle prevents damage to the die mechanism in the event of overloading, the mandrel is accurately positioned and locked in position against the rolling forces exerted by the dies and the supports prevent the mandrel from buckling under the forces exerted upon it by the rolling operation.

The hydraulic advancing and rotating tube mechanism insures accurate advancement and rotation of the tube as it is rolled and the amounts of advance and rotation as well as the timing thereof in the cycle of operations can be accurately controlled and adjusted. The chucks guide and hold the tube accurately during the operation of the machine. The chucks can be adjusted to accommodate tubing of different sizes while the saddle is constructed so that rolls for operating on tubing of different sizes can be readily placed in the machine. All of these factors contribute to the efficient operation of the machine.

I claim:

An apparatus for reducing the diameter of tubes and the like comprising a main supporting frame; an elongated sub-frame extending toward the entry end of the apparatus and secured at one of its ends to said main frame; a pivot mounted on said sub-frame remote from said main frame; an elongated tiltable frame member supported on said pivot and adapted to be moved in a vertical plane about said pivot from a lowered position to a raised position and having one end disposed adjacent said main frame; interengaging means on said main frame and said tiltable frame member for aligning said tiltable frame member with respect to said main frame when said tiltable frame member is in said lowered position; a mandrel mounted on said tiltable frame member; a slidably mounted support member for the end of said mandrel remote from said main frame; bearing means for supporting said mandrel on said support member; means for advancing said mandrel support member and said mandrel carried thereby toward said main

frame and retracting it therefrom; and means for locking said mandrel support member in advanced position, said locking means comprising a seat on one of said members, said seat being arcuate about an axis extending transversely of said tiltable frame member, a rotatable locking means mounted on the other of said members, said rotatable locking means having an arcuate portion engageable with said arcuate seat to lock said mandrel support member in position and having a portion adapted to clear said seat and release said mandrel support member, and means for rotating said locking means between locking and releasing position with respect to said seat.
